UNITED STATES PATENT OFFICE.

HENRY TROTTER AND ELMER BELL, OF ANDERSON, MISSOURI.

REEL FOR TAKING UP AND PAYING OUT WIRE.

1,120,172.

Specification of Letters Patent.

Patented Dec. 8, 1914.

Application filed July 3, 1914. Serial No. 848,932.

To all whom it may concern:

Be it known that we, HENRY TROTTER and ELMER BELL, citizens of the United States, residing at Anderson, in the county of McDonald and State of Missouri, have invented certain new and useful Improvements in Reels for Taking Up and Paying Out Wire, of which the following is a specification.

10 The present invention relates to an improved reel for taking up and paying out wire, and has for its object to provide a device of this character which embodies novel features of construction whereby long 15 lengths of wire can be conveniently handled without danger of twisting and bending the same so as to detract from the value thereof. A further object of the invention is to provide a device of this character which is comparatively 20 simple and inexpensive in its construction, which is of a portable nature and can be readily moved from place to place, which admits of the coils of wire being readily applied to the reel or removed therefrom, and which includes novel guide means 25 for causing the wire to wind evenly upon the drum as it is taken up.

With these and other objects in view, the invention consists in certain novel combinations and arrangements of the parts as will 30 more fully appear as the description proceeds, the novel features thereof being pointed out in the appended claims.

For a full understanding of the invention, 35 reference is to be had to the following description and accompanying drawing, in which:—

Figure 1 is a top plan view of a reel for taking up and paying out wire, constructed 40 in accordance with the invention. Fig. 2 is a side elevation of the same. Fig. 3 is a transverse sectional view on the line 3—3 of Fig. 1. Fig. 4 is an enlarged side elevation of the laterally swinging guide arm. Fig. 5 is a front elevation of the same. Fig. 6 is a detail view of the brake band releasing lever, 45 showing the same by full lines in inoperative position, and by dotted lines in operative position.

Corresponding and like parts are referred to in the following description and indicated in all the views of the accompanying drawing by the same reference characters.

The supporting framework upon which 50 the mechanism to be hereinafter described is

mounted, is shown in the present instance as composed of parallel and horizontally disposed side bars 1 connected by the transverse strips 2 and supported by the legs 3. The side bars 1 are each provided at points 60 between its ends with a bearing 4. A short shaft 7 is journaled in one of the bearings 4, said shaft being formed with an angular socket 7^a at its inner end and being provided at its outer end with a pulley 8 which is provided with sprocket teeth 9. A corresponding short shaft 10 which is in alinement with the shaft 7 is journaled within the other bearing 4, said shaft having an angular socket at its inner end 10^a and being provided 65 at its outer end with a crank handle 11. A brake drum 12 may be applied to the inner end of the shaft 10. It will also be observed that each of the sockets 7^a and 10^a have one side thereof cut away to provide 70 a lateral opening.

The body of the drum 12 is preferably tapered so that coils of wire can be readily removed therefrom or placed thereon, and the large end of the drum or reel is formed 80 with a fixed head 13, while the small end of the drum or reel 12 is provided with a removable head 15. Suitable fastening members such as the screws 16 may be provided for holding the removable head 15 in position, although this head can readily be dismounted when it is desired to place a coil of wire upon the reel or remove it therefrom. Extending longitudinally through the body 85 of the drum or reel 12 is a bar 50, the ends 90 of the bar projecting beyond the ends of the drum to provide polygonal lugs 50^a adapted to be received within the angular sockets 7^a and 10^a of the short shafts 7 and 10. The reel is detachably applied to these short 95 shafts and in order to place it in position or remove it therefrom the short shafts are turned into such a position that the lateral openings of the sockets 7^a and 10^a provided by the cut away sides thereof face upwardly. 100 The polygonal lugs 50^a at opposite ends of the reel 12 may then be dropped downwardly into the sockets 7^a and 10^a through the lateral openings in the sides thereof, or lifted out of the said sockets. In order to 105 lock the polygonal lugs 50^a within the respective sockets 7^a and 10^a, suitable keys 51 may be provided which pass through corresponding openings in the polygonal lugs 50^a and sides of the sockets 7^a and 10^a. 110

These keys 51, however, can be readily removed for the purpose of placing the reel 12 in position or removing it therefrom.

A brake band 17 which is suitably secured 5 at 18 to the main frame passes around the brake drum 14 and is carried to one end of the frame, where it passes under a tension bar 19 and has the extremity thereof secured to a shaft 20. A handle 21 is applied to one 10 end of the shaft 20 for winding or unwinding the ends of the brake band as may be found desirable, a suitable pawl and ratchet 22 being employed in connection with the shaft 20 to prevent backward rotation thereof after an adjustment has once been obtained. Springs 23 engage opposite ends of the brake band tension bar 19 and normally force the same downwardly so as to draw the brake band tightly around the 15 brake drum 14. An L-shaped releasing lever 24, shown more clearly by Fig. 6, is pivoted under one end of the bar 19, the long arm thereof being provided at its extremity with a handle 25, while the short arm thereof is provided with a notched seat 26. When the notched arm of the releasing lever is swung downwardly away from the bar 19, the springs 23 force the bar downwardly so as to tighten the brake band around the 20 brake drum, although when the notched arm of the lever is swung upwardly, as indicated by dotted lines on Fig. 6, until the end of the bar is seated in the notch 26, the bar is moved upwardly against the action of the 25 spring 23 so as to relieve the tension in the brake band 17 and release the brake.

For the purpose of causing the wire to wind evenly upon the reel, a laterally swinging guide arm 27 is employed, said arm being 40 pivoted at 28 to a bracket 29 upon a transverse bar 30. The upper end of the guide arm 27 is formed with a fork 31 through which the wire passes as it is wound upon or unwound from the reel. A shaft 32 connects the two arms of the fork 31 at the ends thereof and a spring flap 33 is hinged thereon, a spring 34 being provided which holds the flap yieldably within the fork, although it is adapted to swing momentarily. 45 in either direction when a splice or enlarged portion in the wire passes through the guide fork. The lower end of the spring flap 33 may be notched at 35 for coöperation with the base of the fork 31 to provide a guide eye through which the wire must pass and be directed in its movements thereby as it is wound upon or unwound from the reel.

A pulley 36 corresponding to the pulley 8 of the shaft 10 is mounted upon one end of the shaft 30, said pulley being provided with sprocket teeth 37. An endless belt 38 passes around the two pulleys 36 and 8 and is formed with a series of openings 39 to engage the teeth 37 of the pulley 36 and the teeth 9 of the pulley 8. These openings 39

are arranged in a straight line, although the edges 38^a of the belt 38 are inclined back and forth so as to be disposed at an inclination to the line of movement of the belt defined by the row of perforations 39. This 70 endless belt 38 passes loosely through a loop 40 at the end of a link 41 which projects laterally from the guide arm 27 and is pivotally connected at 42 to an intermediate part thereof. One side 40^a of the loop 40 may be hinged as indicated at 40^b so that it can be swung outwardly to open the loop 40 for the purpose of inserting the belt 38 therein or removing it therefrom. A suitable latch 40^c may be provided for normally holding 75 the swinging side 40^a of the loop 40 in a closed position. The ends of the loop 40 engage the inclined edges 38^a of the endless belt 38 so that as the belt travels upon the pulleys 37 and 8 a longitudinal back and forth movement is imparted to the link 41. This serves to swing the guide arm 27 back and forth so that the wire passing through the fork thereof is wound evenly upon the reel 12. The spring flap 33 which is mounted within the fork 31 normally holds the wire at the base of the fork, although when a spliced portion or the like reaches the guide fork the spring flap 33 will temporarily swing to one side to admit of the said 85 spliced portion passing through the fork.

Having thus described the invention, what we claim as new and desire to secure by Letters Patent, is:—

1. A device of the character described including a frame, a shaft journaled thereon, a reel having an operative connection with the shaft, means for turning the reel, a pulley upon the shaft, a second pulley, an endless belt passing around the two pulleys 100 and formed with edges which are inclined from side to side with respect to the direction of movement of the belt, a transversely moving guide arm provided with guide means for engaging wire or the like wound upon the reel, and means carried by the guide arm for engagement with the inclined edges of the belt to actuate the guide arm.

2. A device of the character described including a main frame, a shaft journaled thereon, a reel having an operative connection with the shaft, means for turning the reel, a pulley applied to the shaft, a second pulley, sprocket teeth projecting from the two pulleys, an endless belt passing around the two pulleys and provided with a series of openings adapted to engage the sprocket teeth thereof, the edges of the belt being inclined from side to side with respect to the direction of movement of the belt, a transversely swinging guide arm provided with guide means for engaging wire or the like being wound upon the reel, and a link having one end thereof pivotally connected to the swinging guide arm, while the opposite 115 120 125 130

end thereof is formed with a loop which loosely receives the endless belt and is acted upon by the inclined edges thereof to swing the guide arm back and forth.

5 3. A device of the character described including a main frame, a reel, means for mounting the reel upon the main frame, means for turning the reel, a transversely movable guide arm having a forked end, a 10 flap pivotally mounted within the forked end of the guide arm for holding wire or the like passing through the fork at the base thereof, yielding means normally holding the flap in operative position but permitting the same to swing in either direction as required, and means for actuating the 15 transversely movable guide arm.

4. A device of the character described including a main frame, a shaft journaled 20 thereon, a reel having an operative connection with the shaft, means for turning the reel, a pulley applied to the shaft, a second pulley, sprocket teeth projecting from the two pulleys, an endless belt passing around

the pulleys and formed with a series of 25 openings engaging the sprocket teeth thereof, the edges of the endless belt being inclined from side to side with respect to the direction of movement of the belt, a transversely swinging guide arm having a 30 forked end, a swinging flap mounted within the forked end of the guide arm for normally holding the wire or like at the base of the fork, and a link member having one end thereof loosely connected to the swinging 35 guide arm, while the opposite end thereof is formed with a loop loosely receiving the endless belt so as to be acted upon by the inclined edges thereof to swing the guide 40 arm back and forth.

In testimony whereof we affix our signatures in presence of two witnesses.

HENRY TROTTER.
ELMER BELL.
